UNITED STATES PATENT OFFICE.

CHARLES H. GROVES, OF BEAUMONT, TEXAS.

SHOCKER.

1,343,775.

Specification of Letters Patent. Patented June 15, 1920.

Application filed June 25, 1918. Serial No. 241,849.

To all whom it may concern:

Be it known that I, CHARLES H. GROVES, a citizen of the United States, residing at Beaumont, in the county of Jefferson and 5 State of Texas, have invented certain new and useful Improvements in Shockers, of which the following is a specification.

This invention relates to grain shockers.

One of the objects of this invention resides in the provision of a shocker and capper which is automatic in operation.

Another object of this invention resides in the provision of a shocker and capper which automatically distributes the bundles 15 to a compressor where it is capped and automatically discharged therefrom.

A still further object of this invention resides in the provision of a shocker and capper which automatically compresses the 20 shock and disposes it in an upright position prior to discharging it therefrom.

A still further object of this invention resides in the provision of a shocker and capper having an automatic compressor 25 which is adapted to manipulate certain means for preventing the delivery of bundles thereto during the period it is discharging the shock therefrom.

A still further object of this invention resides in the provision of a shocker and capper 30 consisting of means for automatically compressing the shock and releasing it prior to delivering it to the ground.

With these and other objects in view this 35 invention resides in certain novel features of construction, arrangement of parts, and combination of elements to be more particularly described in the specification herewith and pointed out in the appended claims, it 40 being understood that the right is reserved to resort to such changes in construction as come within the scope of the claims.

In the accompanying drawings:

Figure 1 is a plan view of a shocker constructed in accordance with this invention;

Fig. 2 is a side view of the structure shown in Fig. 1;

Fig. 3 is a vertical sectional view approximately on the line 3-3 of Fig. 2;

Fig. 4 is a similar view approximately on line 4-4 of Fig. 2 showing the compressor in its discharging position;

Fig. 5 is a detail sectional view on a portion of the lower conveyer showing one of 55 the teeth thereof in working position with

full lines and collapsed position with dotted lines;

Fig. 6 is a detail perspective view of one of the pivoted teeth to the elevating conveyer;

Fig. 7 is a detail perspective view of a portion of the rear side of the shocker frame showing means whereby the distributing forks are manually controlled;

Fig. 8 is a detail perspective view of one 65 set of the distributing forks;

Fig. 9 is a detail perspective view of the other set of distributing forks;

Fig. 10 is a detail perspective view of one set of the forks forming the automatic 70 trap.

In the present embodiment of this invention, the letter B in Fig. 2 designates a portion of the delivery side of a binder. To better set forth the operation of the structure involved in this invention, the binder herein illustrated is provided with a shaft S which is manipulated by the usual means employed for transmitting power from the bull wheel of the binder to successfully 75 manipulate the several auxiliaries of the complete binder. The aforesaid shaft S is provided with a sprocket wheel S' which together with a chain C transmits motion to the mechanism embodying this invention. 85

Pivotedly secured as at 5 to the frame F of the binder B is a laterally extending frame 6 consisting of a superstructure 7 which is supported by vertical standards 9 and inclined braces 10 that not only connect the superstructure to the frame 6, but are utilized to support a conveyer 11 to be hereinafter described.

The aforesaid superstructure 7 of the frame 6 consists of substantially horizontally disposed rails a, b and c, which together with rails, d e, and slats f form what is herein termed a hopper.

Rigidly secured to the braces 10 is an upwardly inclined platform 12 having a 100 plurality of notches n therein to receive the sprocket wheels 14 which are supported on shafts 15 and 16 that are journaled adjacent the upper and lower ends of the inclined braces 10.

Trained over the sprocket wheels 14 are conveyer chains 17 to which are pivotally secured at predetermined distances apart a plurality of teeth 18. The teeth 18 as herein disclosed are provided with runners 19 110

which bear on the platform 12 during the elevation of the bundles and as soon as the bundles have reached an elevated position adjacent the upper sprocket wheels 14, the 5 runners 19 will straddle the sprocket wheels whereupon the teeth will assume an inwardly inclined position to prevent their tendency to drag the bundles beneath the platform 12.

10 Suitably secured to the rail *a* of the hopper is a platform 20 having a plurality of slots *s* therein for the passage of the ends of grate fingers to be hereinafter set forth.

15 Rotatably supported by the rail *a* adjacent the inner and outer edges of the platform 20 are shafts 21 and 22 to which are splined or otherwise fixedly secured a plurality of sprocket wheels 23 having trained thereover a plurality of conveyer chains 24 20 that carry a multiplicity of spaced teeth 25 for engagement with the bundles that are delivered from the inclined conveyer 11 to convey them to certain points beneath the platform 20.

25 Certain of the aforesaid shafts are preferably adjustable to permit the chains to be tightened and as common means heretofore employed will be used they are omitted from the drawings.

30 Journaled at its forward end in the rail *r* of the frame 6 is a wheel carriage 26 having a spindle 27 rigidly secured thereto for the reception of a wheel 28 to support the frame beyond its connection with the binder

35 frame. This wheel carriage is provided with means for adjusting the height of the shocker with that of the binder and since various adjusting means can be successfully employed to attain the desired results, a

40 simple structure is herein disclosed which involves the employment of a chain 30 fastened to the terminal *t* of the carriage and is adjustably connected to a hook *h* secured to one side of the frame 6, therefore it is 45 apparent that as the chain is shortened or lengthened, the carriage will either raise or lower the shocker frame.

45 Rigidly secured to said frame 6 is a laterally extending tubular bearing 31 which 50 is forwardly offset from the front rail *p* of the frame to receive a rotatable shaft 32. Secured to the inner end of the shaft 32 is a double crank arm 33, one end of which is connected to a link 34 that is pivoted to and 55 manipulated by a similar link fastened to a rod 35 that extends to the driver's seat where suitable levers (not shown) are provided for rocking the rod 35 and rotating the shaft 32.

60 Splined or otherwise secured to the outer end of the shaft 32 is a U-shaped bracket 36 having bearings adjacent the terminals of its arms 37 for the reception of the trunnions 38 of a compressor 39.

65 The aforesaid compressor consists of a frame 40 which supports the trunnions 38,

70 hinged sides 41 and hinged shutters 42. In order to divide the inclosure formed by the hinged sides and the shutters in compartments, a plurality of partitions 43 are rigidly supported by the frame 40, said partitions being herein constructed in the form of open grates but any approved construction may be as successfully employed to accomplish the initial functions of the grate.

75 Fixedly secured to the frame of the compressor are a plurality of runners 44 which are adapted to engage the ground and support the weight of the compressor during the period it is in its discharging position.

80 Each of the shutters is provided with cam-shaped lugs 45 which are adapted to engage pins 46 carried by the frame 40 to retain the shutters in closed position while the compressor is being filled. To facilitate the manipulation of the shutters to permit the discharge of the shock from the compressor trips 47 are hingedly secured to the frame 40 and extend in contact with the shutters as at 40' whereupon the shutters are lifted against the tension of springs 40" upon the 85 engagement of the trips with the ground and during the advancement of the binder the shock will force the shutters open against the tension of the springs 40" which will 90 close the shutters after the shock is discharged.

95 Depending from the rail *c* of the superstructure of the frame 6 are a plurality of brackets 48 adjacent the lower ends of which are journaled shafts 49 having certain portions thereof provided with cranks 50 that carry rollers 51 for contact with the yieldable sides of the compressor to permit the shock to be compressed when these rollers are forced inwardly. One of the aforesaid 100 shafts 49 is provided with a second crank 52 between which and one of the arms 37 of the U-shaped bracket 36 is hingedly secured an adjustable link 53 to facilitate the disengagement of the compressor cranks 50 105 from the sides of the compressor during the descent of the U-shaped bracket 36 and the compressor. Since it is necessary to simultaneously actuate the compressor cranks 50 to exert an inward pressure on opposite sides 110 of the shock, the shafts 49 are provided with crank arms 54 that are connected for movement in opposite directions by links 55 which in turn are pivotally secured to the opposite ends of a rocker arm 56 that is journaled 115 midway between the pivotal connections of links 55 as at 57, thus it will be seen that as one crank arm 54 is moved to compress the shock within the compressor, the other crank arm will similarly exert a like pressure for 120 the reason that the rocker arm 54 will impart the proper motion thereto.

125 Secured to one of the crank arms 54 and one of the standards 9 of the frame 6 is a strong retractile coil spring 58 which is 130

65

adapted to pull that arm to which it is connected toward the standard 9 upon the actuation of a spring retained trip 59, that releases a catch 60 as the guide roller 61 on 5 the compressor frame assumes an elevated position prior to entering a guide 62 that is rigidly secured to the standards 9 for maintaining the compressor in an upright position while discharging the shock therefrom.

10 Adapted to tilt the compressor is a lever 63 which is pivoted as at 64 and is held in engagement with the roller 61 by a strong retractile coil spring 65, said coil spring being adapted to rock said lever 63 upon the release of the trip 66 by a cranked rod 67 which extends to suitable manipulating means (not shown) adjacent the seat of the driver. Through the provision of the aforesaid lever 63 and coil spring 65 the compressor is tilted 15 so that the shutters will assume a position to the rear of the shocker and upon the entrance of the roller 61 in the guide 62, the compressor will descend through the manipulation of the shaft 32. As the shaft 32 is rotated to lower the compressor the lever 63 is returned to its normal position by an adjustable link 68 connected as at 69 to the lower end of the double crank arm 33 and as at 70 to the lever 63. The link 68 is provided with a slot 71 at its connection 70 with the lever 63 to permit the spring 65 to actuate the lever 63 without similarly exerting a pulling action on the double crank arm 33.

Pivotal secured to the rails *b* of the superstructure is an inner grate 72 having upwardly directed cranks 73 and 74 at the ends of its shaft 75 and a vertically disposed lug 76 adjacent the crank 73. Also pivotally supported by the rail *b* of the superstructure is an outer grate 77 having an upwardly directed crank 78 at the forward end of its shaft 78' and a downwardly directed crank 79 at the rear end of its shaft. This outer grate has its shaft provided with 45 a crank arm 80 to which is pivotally connected a trip lever 81 that is provided with a bill 82 for engagement with the aforesaid lug 76 on the shaft 75 of the inner grate, therefore when the outer grate is rotated 50 through the engagement of the advanced bundle with the vertical fingers 83, the inner grate will be tilted upwardly and through the provision of coil springs 84 fastened to the cranks 73 and 78 the grates 55 will remain tilted whereupon the progress of the next bundle will be interrupted by the upstanding fingers 85 of the inner grate and its weight will over balance the tension of the coil spring and cause the fingers 86 60 to assume their initial vertical position and the fingers 85 to assume their horizontal position as the bill 82 of the trip lever 81 previously disengaged the lug 76 on the shaft 75 so that it was free to return without 65 out interference with the position of the

outer grate. After the inner grate has discharged the bundle thereon, the horizontal fingers of the inner grate form a platform for the passage thereover of the next proceeding bundle which encounters the upstanding (normally horizontal) fingers 87 of the outer grate and since the weight of this advancing bundle over-balances the tension of the coil spring 84, it will cause the horizontal (normally vertical) fingers 88 to 70 tilt, whereupon the bundle like those previously mentioned will be deposited on pivoted traps 89 journaled in the rails *c* of the superstructure for delivery to the compressor. The resilient connections between 75 the grates and traps are so disposed that upon rotating the cranks 73 and 78 beyond certain points, the springs will retain the grates in fixed position until interrupted by either the advancement of the bundles or 80 their weight on their raised horizontal (normally vertical) fingers.

The normally horizontal fingers of the grates and traps are retained in contact with their adjacent shafts by the exertion of the 90 coil springs on the cranks 73 and 78 therefore it is apparent that suitable stops are provided to limit their movement in one direction.

The aforesaid traps are provided to retain 95 any bundles which are discharged from the grates during the period that the compressor is discharging the shock therefrom and in order to render the traps inoperative during this period, each shaft of the traps is provided with a lug 90 that is engaged by an adjustable notched latch bar 91 slidably supported by the forward standard 9 of the frame and having its lower end directed as at 92, in the path of the U-shaped bracket 100 105 36, thus it is apparent that it is necessary to raise said compressor bracket before the latch bar will release the traps for manipulation.

Should the grates fail to automatically assume the proper positions for successfully discharging the capping bundle to the compressors, manually manipulated means are provided with which the fingers of the 110 grates can be adjusted to the desired positions. In producing a simple mechanism for attaining the above functions, a slidable bar 93 is provided which has lugs 94 thereon for engagement with the cranks 74 and 79 and as these lugs are brought in contact with the 115 cranks 74 and 79, the inner grate is directed to its normal position and the outer grate is directed to a position to discharge the capping bundle therefrom on the trap below where it is delivered to the center compartment of the compressors. This means for manually controlling the grates from the seat of the driver by a rope 95 is of such construction that either grate can operate 120 independently of the other, but can be simul- 125 130

taneously manipulated to assume the proper working position.

To facilitate the return of the compressor to its normal position for receiving an additional supply of bundles after having discharged the shock, therein, leaf springs 96 are supplied. These leaf springs are of sufficient tension to overbalance the weight of the compressor when tilted and will readily 10 return the compressor to its horizontal position as soon as the shock has been discharged therefrom.

In order to retain the sides of the compressor in their expanded positions after 15 the compressor arms 50 are released, suitable springs 97 are fastened at one of their ends to the frame of the compressor with their opposite ends exerting an outward pressure against the side of the compressor 20 to release the side pressure on the shock.

The shafts 16 and 21 are provided with meshing gear wheels 98 and 99 in order that the conveyer chains 24 will operate in the opposite direction to the conveyer 11 as the 25 chain C rotates the shaft 16.

In operation the bundles of grain are deposited on the conveyer 11 from the discharge end of the binder and are elevated until engaged by the conveyer chains 24 30 whereupon the advanced bundle is conveyed to the outer grate and upon contacting with the fingers 83 it will tilt the outer grate until its normally horizontal fingers 87 stand in an upright position which manipulation of the outer grate will cause the inner grate to similarly tilt by the action of the trip lever 81 on the lug 76, in which position they will remain under the influence of the coil springs 84. After the outer grate 35 has assumed the aforesaid position the advanced bundle is discharged therefrom on to the trap 89 which deposits the advanced bundle in the outer compartment of the compressor. During the passage of the advance 40 bundle from the grate to the compressor the upstanding (normally horizontal) fingers 85 of the inner grate are encountered by the second bundle and since its weight over-balances the tension of the spring 84 it is deposited on the trap therebelow where 45 it is discharged to the inner compartment of the compressor. Now that the outer grate has its normally horizontal fingers disposed in an upright position with its normally vertical fingers 86 disposed in the position 50 formerly occupied by the horizontal fingers 87, the third bundle is permitted to pass over the fingers 85 of the inner grate for they have been previously returned by the 55 second bundle and upon abutting the upstanding horizontal fingers of the outer grate, the third bundle will over-balance the spring 84 and cause the outer grate to tilt to its original position whereupon it will be deposited on the trap beneath the outer grate 60 65

from which it will be delivered to the center compartment of the compressor.

After the compressor has been filled the rod 67 is rocked to release the trip 66 whereupon the coil spring 65 will rock the lever 70 63 which through its engagement with the roller 61 will tilt the compressor in its bracket 37 until said roller strikes the trip 59 to release the catch 60, then the coil spring 58 causes the compressors 50 to exert an inward pressure on the sides of the compressor. After the compressor has been tilted and before it proceeds on its downward course the outer grate discharges a bundle to the trap beneath from which it is 80 deposited on the upstanding bundles yet to be discharged from the compressor to form the usual cap. In order to permit the descent of the compressor the rod 35 is rocked to break the link connections 33 to the 85 pivoted bracket and as the compressor descends, the compressors 50 are retracted by the links 53 and cranks 52 and upon the engagement of the hinged trips with the ground the shutters 42 are elevated to disengage their catches 45 whereupon the shutters will open and the shock will be discharged from the compressor. During the period of time consumed to discharge the 90 shock from the compressor the latch bar 91 will engage the lugs 90 of the traps and retain them in operative positions until the compressor is again returned for receiving the bundles.

After the shock has been discharged from 100 the compressor the shutters 42 will be closed by the springs 40" and the compressor will return to its normal position under the influence of the springs 96 upon the roller being ejected from its guide by the manipulation of the bracket 36 through the instrumentality of the rod 35 and shaft 32, which is assisted in its return movement by a retractile spring 100. During the return of the compressor to its receiving position, the 110 rocker arm 63 will be returned to its normal position and the latch bar 91 will be released from the lugs on the traps to render them operative until again locked by the descent of the compressor. With the 115 compressor again in its receiving position each element will assume a position to be successfully manipulated to gain automatically form and discharge the shock with a cap thereon.

Having thus fully described this invention what I claim is:—

1. In a grain shocker, a frame adapted to receive bundles, swinging sides hinged to said frame, shafts at the sides of said frame, cranks on said shafts engaged with said sides, and means for rocking said shafts simultaneously in opposite directions.

2. In a grain shocker, a frame adapted to receive bundles, sides hinged to said frame,

shafts at the sides of said frame, cranks on said shafts engaged with said sides, means for rocking said shafts simultaneously in opposite directions, and means tending normally to maintain said shafts in such position that the sides are at the limit movement in one direction.

3. In a grain shocker, a frame adapted to receive bundles, swinging sides hinged to

said frame shafts at the sides of said frame, 10 cranks on said shafts engaged with said sides, a rock arm arranged between said shafts, crank arms on the ends of said shafts, and links connecting the ends of said rock arm with the said crank arms. 15

In testimony whereof I affix my signature.

CHARLES H. GROVES.
